FIG. 7.

FIG. 1 is a perspective view of a door barricade showing my new design as it would be installed upon a door. FIG. 2 is a front elevational view of the left end thereof uninstalled.

FIG. 3 is a top plan view of the right end thereof with the bar shown broken for ease of illustration.

FIG. 4 is a left end elevational view thereof at a slightly larger scale than FIGS. 2 and 3 without the bar in place.

FIG. 5 is a right end elevational view thereof at a slightly smaller scale than FIGS. 2 and 3 with the bar in place.

FIG. 6 is a front elevational view to an even smaller scale of the right end thereof uninstalled and the bar shown broken for ease of illustration.

FIG. 7 is a perspective view of a door barricade similar to FIG. 1 except at a larger scale.

The broken lines are for illustrative purposes only.

I claim:

The ornamental design for a door barricade, as shown and described.
